UNITED STATES PATENT OFFICE.

ERASTUS WOODWARD, OF BOSTON, MASSACHUSETTS.

DESIGN FOR A SEWING-MACHINE FRAME.

SPECIFICATION forming part of Design No. 12,348, dated July 5, 1881.

Application filed April 23, 1881. Term of patent 14 years.

To all whom it may concern:

Be it known that I, ERASTUS WOODWARD, of Boston, in the county of Suffolk and State of Massachusetts, a citizen of the United States, 5 have invented a certain new and useful Design for a Frame for Sewing-Machines, of which the following is a full, clear, and exact description, reference being had to the accompanying drawings, forming a part of this specification, in explaining its nature, in which—

Figure 1 is a front elevation of my improved frame, and Fig. 2 is a side elevation.

The object of this design is to provide a neat and ornamental frame for supporting the 15 operative parts of a sewing-machine.

It consists of the body a , the curved upwardly-projecting portion or neck a' , the flat table a^2 , supported thereon, and the legs a^3 , extending from the body a substantially as represented. The neck preferably is circular or 20 oval in cross-section.

The legs may have the straight outline a^4 upon the outer edge, or may be somewhat curved, without departing from the spirit of 25 my invention.

The frame preferably is a cast-iron shell, but it may be made in two or more parts, if desired.

The table a^2 supports various parts of the stitch-forming mechanism.

The essential features of my design I consider to be, however, the body a , shaped substantially as shown in front and side elevation, having the legs a^3 branching outwardly therefrom, and the curved neck a' extending upwardly and supporting a flat plate or table, a^2 . 35

Having thus fully described my improved design, I claim and desire to secure by Letters Patent of the United States—

The design for a frame of a sewing-machine, consisting of the body a , the legs a^3 , branching therefrom substantially as described, and the curved upwardly-projecting neck a' , bearing or supporting a table, a^2 , all substantially as set forth. 40

ERASTUS WOODWARD.
